L. G. ECONOM

COMBINATION WRENCH

Filed March 25, 1922

Louis G. Econom INVENTOR
BY *Morris Fischstein* ATTORNEY

UNITED STATES PATENT OFFICE.

LOUIS G. ECONOM, OF NEW YORK, N. Y.

COMBINATION WRENCH.

Application filed March 25, 1922. Serial No. 546,559.

To all whom it may concern:

Be it known that I, LOUIS G. ECONOM, a citizen of the United States, residing at the city of New York, in the county of Bronx 5 and State of New York, have invented certain new and useful Improvements in Combination Wrenches, of which the following is a specification.

This invention relates to combination wrenches. One object thereof is to provide 10 a combination wrench which may readily be used both as a "monkey" and a "Stillson" wrench.

Another object of this invention is to provide 15 a wrench of the character described with readily removable gripping jaws adapted to be withdrawn or extended as desired.

A still further object is to provide a practical 20 combination wrench of the character described which shall be simple in construction, easy to manipulate and efficient in operation to a high degree.

Other objects of this invention will in 25 part be obvious and in part hereinafter pointed out.

The invention accordingly consists in the features of construction, combinations of elements and arrangement of parts which will 30 be exemplified in the construction herein-after described and of which the scope of application will be indicated in the following claims.

In the accompanying drawings, in which 35 is shown one of various possible illustrative embodiments of this invention,

Fig. 1 is a vertical elevational view partly in section of a wrench embodying the invention shown in use as a Stillson wrench 40 with the parts adjusted for gripping pipes and the like objects;

Fig. 2 is an elevational view (partly broken away) and in section, showing the wrench in use as a "monkey" wrench with 45 the parts adjusted for gripping nuts and the like objects;

Fig. 3 is a cross-sectional view cut along line 3—3 of Fig. 1;

Fig. 4 is a rear end elevation of the upper 50 portion of the wrench;

Fig. 5 is a detail sectional view cut along line 5—5 of Fig. 1;

Fig. 6 is a perspective view of the cam member for extending and retracting the gripping jaws and for locking the reciprocating shank in position;

Fig. 7 is a perspective view of the washer employed with the jaw cam member;

Fig. 8 is a partial vertical elevation of the tool, showing the head portion thereof; and

Fig. 9 is a front elevation of the key provided for operating the cam member.

Referring in detail to the drawing, 10 indicates the upper jaw, 11 the lower jaw and 12 the handle of a wrench embodying my invention. Secured adjacent the rear edge of the upper jaw and formed preferably integral therewith is the downwardly extending shank 13 adapted to enter the slot 14 of the handle portion 12. The shank 13 comprises an upper portion 13^a of rectangular cross-section, pivoted at 15 to a lower portion 13^b so that the upper jaw 10 may rock about the connecting pin 16, to provide the necessary play for the upper gripping jaw when the wrench is adjusted for plumbing or other similar work. A lock cam 17 is provided for locking the upper shank portion 13^a against rocking when desired.

This lock cam 17 is shown in Fig. 6 and comprises a cylindrical member having a cut away portion 18, a semi-cylindrical cam face portion 19, a bearing 20 and an operating portion 21. The latter is provided with a counter-sunk depression 22 preferably rectangular in cross section, wherein is inserted a separate key 23 as shown in Fig. 9. A semi-cylindrical opening 17' is provided in the jaw 11 to receive the cam 19. In

locking position, the cam face 19 bears against the shank portion 13^a, as shown in Fig. 2, so that the jaw 10 is prevented from swinging but may reciprocate for use as a monkey-wrench, as in loosening a nut 25. For pipe work, the cam 17 is rotated by 90 means of the key 23 so as to dispose the semi-cylindrical cam face 19 in the opening 17' (see Fig. 1), and then the shank portion 13^a is free to swing forward and backward to permit the jaws 10, 11 to alternately grip and release the pipe 24. The lower portion 13^b of the shank has threads or teeth 26 provided on its front and rear sides for engaging similar teeth or threads

26' on opposite sides of the bore of the knurled nut 27, which is adapted to be manually rotated for locking the shank portion 13^b relatively to the handle 12. The 5 knurled nut 27 has opposed recesses 28 disposed between its threaded portions 26', and when these recesses register with the teeth 26 of the shank, the shank may freely slide axially through the nut 27. A mark 29 is provided on the exterior surface of the knurled nut 27 and cooperates with a mark 29^a on the handle to indicate when the threads 26' of the nut are in engagement with the threads 26 of the shank. In this 10 position, the nut locks the shank against axial movement. When the nut is given a quarter turn from the position in Fig. 2 to the position in Fig. 5, the shank 13 may slide freely without interference by the nut. 15 20 For preventing the shank 13 from being raised above the member 27, a set screw 30 is provided below said member. The set screw enters a groove 31 cut on the one of the side faces of the lower shank portion 13^b 25 and acts as a stop against the lower wall 31' of the groove, when the shank is fully extended. For guiding the shank in its upward travel, a spring member 32 is provided, suitably secured to the handle member as by the screw 33.

The means for adapting and adjusting the wrench for use as a Stillson wrench to grip pipes and the like objects will now be described. The jaws 10, 11 are provided with recesses 34, 35 respectively. These are disposed adjacent the gripping faces 10', 11' and are adapted to receive a pair of toothed jaws 36, 37. Cam means 38, 39 (similar to that already described in connection with 30 the locking cam 17 for the shank 13) are provided for disposing the toothed jaws 36, 37 in the gripping position shown in Fig. 1, or in the non-operative position shown in Fig. 2. Each cam member 38, 39 comprises 35 the operating portion 40 having the rectangular depression 41 for the key 23, the cylindrical cam face 42 and the end 43. The latter in this instance enters a journal washer 44 having an opening 45 of the form shown 40 similar to the cross-section of the end 43 for providing the eccentricity necessary for the lowering and raising of the toothed jaws 36, 37. Circular openings are provided in the jaws 10, 11 to receive the operating portions 45. Similar openings are provided in the jaws for holding the bearing washers 44. The toothed jaws 36, 37 have elongated slots 46, 47 formed therein wherethrough pass the cams 38, 39. 50 55 60 65 60 The operation of the wrench will now be clear. Assume the tool with the jaws open and the teeth extending. The toothed jaws 36, 37 are first disposed in their non-gripping position by the turning of their respective cams 38, 39 with the key 23. The shank 13

is locked against rocking by operating the cam 17 and the wrench is now adapted to be used as a monkey wrench (see Fig. 2). To adjust the latter for operation as a Stillson wrench, the shank 13 is released by turning the cam 17 back, and the jaws 36, 37 are extended into gripping position as shown in Fig. 2, by turning the cams 38, 39, respectively, with the key 23 so that their cam faces cause the toothed jaws 36, 37 to be extended in gripping position. 75

An added advantage of the wrench I have provided resides in the fact that the jaws 36, 37 are removable and may be replaced when worn away, thus extending the life 80

It will thus be seen that there is provided a device in which the several objects of this invention are achieved and which is well adapted to meet the conditions of practical use. 85

As various possible embodiments might be made of the above invention and as various changes might be made in the embodiment above set forth, it is to be understood that all matter herein set forth or shown in the accompanying drawings is to be interpreted as illustrative and not in a limiting sense. 90

Having thus described my invention, I claim as new and desire to secure by Letter Patent:—

1. In a combination wrench, the combination of a handle having a slot formed therein, a shank adapted to be reciprocated in said slot and having a groove formed on the lower portion thereof, means for permitting said shank to have a rocking movement, means for preventing said rocking movement when desired, resilient means for maintaining and guiding the shank when reciprocated, and means for preventing the withdrawal of the shank from the slotted handle, said means comprising a set-screw adapted to abut the shank adjacent the grooved face thereof. 100

2. A combination wrench including a handle provided with a stationary jaw, a movable jaw having a shank axially movable in the handle, said shank being formed of a plurality of sections pivotally connected together, the section of said shank adjacent the movable jaw being capable of rocking forwardly and rearwardly in the handle, and means for locking the rocking portion of the shank against rocking movement while permitting the shank to move axially, each of said jaws being provided with a toothed insert capable of moving in a straight line, and means for moving said inserts toward or away from each other. 110

3. A combination wrench including a handle provided with a jaw and having a bore, a shank axially movable in the bore of the handle and carrying a second jaw, means for locking the shank against axial movement in the handle, said shank being 115 120 125 130

formed of upper and lower sections pivotally connected together and the upper section carrying the second jaw and being capable of rocking movement forwardly and rearwardly, and a cam arranged in the handle and adapted to engage the shank for locking the upper portion of the same against

rocking movement, each of said jaws being provided with a rectilinearly movable toothed insert, and means for moving said inserts toward and away from one another.

In testimony whereof I affix my signature.

LOUIS G. ECONOM.
